Attorney

UNITED STATES PATENT OFFICE.

AMOS BOUCHER, OF MONCLOVA, OHIO.

DOOR-SECURER.

SPECIFICATION forming part of Letters Patent No. 278,863, dated June 5, 1883.

Application filed January 26, 1883. (No model.)

To all whom it may concern:

Be it known that I, AMOS BOUCHER, of Monclova, in the county of Lucas and State of Ohio, have invented certain new and useful Improvements in Door-Securers; and I do hereby declare the following to be a full, clear, and exact description of the invention, such as will enable others skilled in the art to which it appertains to make and use the same.

10 My invention relates to an improvement in door-securers, the object of the same being to provide a device of this character which shall combine simplicity and economy of construction with durability and efficiency in use; and 15 with these ends in view my invention consists in the parts and combinations of parts, as will be more fully described, and pointed out in the claims.

In the accompanying drawings, Figure 1 is 20 a view in perspective, showing my improvement in a closed or locked position. Fig. 2 is a similar view, showing the parts in open position. Fig. 3 is a longitudinal sectional view, showing the parts in closed position; and Fig. 25 4 is a modification.

A represents the body or main portion of my securer, having a plain or smooth upper face throughout its entire length, and provided on its lower face with the teeth or spurs *a*, 30 adapted to be forced into the door-sill or door-jamb and hold the device in proper position. This lower face is also provided with the shoulder *B*, which latter is adapted to bear against the edge of the sill or the edge of the jamb, as 35 the case may be, and prevent the device from being moved farther inward as the door is closed.

C is a hinged leaf, pivotally secured to the rear end of the body *A*, and provided with the 40 legs or standards *D*, which latter, when the leaf *C* is turned down on the body *A*, forms an abutment against which the door bears. This hinged leaf *C* is also provided with the spring-catches *E*, which latter engage the side edges 45 of the body *A* when the parts are folded together, and prevent the leaf from being thrown back when pressure is exerted against the door.

F is a sliding wedge, loosely held and guided on the upper surface of the body *A* by the 50 screws *d*. This wedge is adapted to be moved

forward, so as to fill up any space between the edge of the door and the sill or jamb, and thereby prevent the teeth or spurs from working loose if continued pressure is exerted against the door. This wedge is so shaped and situated as to engage the door as the latter is closed, and be automatically moved thereby outward between the door-frame and the door. 55

To lock or secure a door by my device it is simply necessary to open or throw back the leaf *C* to the position shown in Fig. 2, and place the toothed end of the body *A* either against the sill or door-jamb, with the shoulder *B* thereof resting against the edge of the stud, sill, or jamb. The door is then closed, which 60 forces the teeth or spurs *a* into the door frame or sill and holds the device securely in position. If the door does not sufficiently close on the body *A* to hold it in position, the wedge can be forced between the body *A* and the door; 65 or it can be so placed that the door will engage therewith while closing and automatically move it outward, so as to force the teeth into the door-frame. After the door has been closed on the body *C* is folded over on the 70 body *A*, and the spring or springs thereof engage the said body and hold the said wing down in closed position. This brings the abutment *D* against the inner edge of the door and forms a stop, and prevents the door from being opened 75 when pressure is exerted thereon from the outside.

In the modification shown in Fig. 4 I have dispensed with the springs and employ in their stead the bolt *M*, which latter is movably secured on the top face of the hinged leaf. This bolt is provided with the thumb-piece *m* and the sharpened end *n*, which latter is adapted to be forced into the door and hold the hinged leaf in position. When it is desired to release 80 the door or remove the securer therefrom, it is simply necessary to withdraw the bolt *M* and throw the hinged leaf back, which leaves the door free to be opened. 85

My invention is simple in construction, durable and effective in use, can be folded within a small compass, is especially adapted for travelers, and can be manufactured at a small initial cost. 95

It is evident that slight changes in the con- 100

struction and relative arrangement of the several parts might be resorted to without departing from the spirit of my invention; and hence I would have it understood that I do not limit myself to the exact construction shown and described, but consider myself at liberty to make such changes and alterations as fairly fall within the spirit and scope of my invention.

Having fully described my invention, what I claim as new, and desire to secure by Letters Patent, is—

1. The combination, with the body provided with spurs and a shoulder, of a hinged leaf having legs or standards adapted to form an abutment, and provided with a spring or springs for locking the hinged leaf over on the body, substantially as described.

2. The combination, with the body provided with spurs and a shoulder, and a sliding wedge secured to the said body, of the hinged leaf, the end of which forms an abutment for the door, and a spring or springs for locking the

hinged leaf over on the body, substantially as described.

3. The combination, with the body provided with spurs, and a sliding wedge secured to the said body, of a leaf pivotally secured to the rear end of the body, and adapted to be folded over on the body and form an abutment.

4. The combination, with the body provided with spurs, and a sliding wedge secured to the said body, of a leaf pivotally secured to the rear end of the body, and adapted to be folded over on the body and form an abutment for the door, and means for holding it in position against accidental displacement.

In testimony whereof I have signed this specification in the presence of two subscribing witnesses.

AMOS BOUCHER.
